SERVICE LINE SHUT-OFF

Eugene Miller, Albany, N. Y.

Application August 5, 1932, Serial No. 627,579

3 Claims. (Cl. 74—423)

My invention relates to valve shut-offs and particularly to a means whereby the water supply to a house or building can be shut off at the point where it taps the main without the necessity of excavating the street. Water mains in cities are always placed in the street. Sometimes the main is located beneath the street pavement proper and sometimes the main is placed under the sidewalk near the curb line. This main pipe line is tapered at various points and from these taps, service lines or pipes extend laterally to the buildings along the street. The taps are usually placed in the top of the main and a shut-off cock forms a part of the tap itself. This is generally made of brass. From the shut-off cock a lead pipe extends into the building through a second shut-off cock located under the sidewalk. The pipe line leading from the tap in the main to the building is, of course, covered with dirt or other filling material, and on top of this is laid the wearing surface of the pavement. This lateral pipe line is, therefore, subjected to vibrations due to heavy traffic and serious leaks often occur at points in this line. When a service line breaks, water from the main escapes into the soil underneath the pavement and, in addition to the loss of a considerable volume of water, it is not at all infrequent to have the pavement so seriously undermined as to collapse or cave in. In any event, when a leak occurs in a service line, it becomes necessary to take up the pavement and excavate down to the main in order to reach the shut-off cock. Until this is done water continuously escapes from the main.

The principal object of my invention is to supply a device which will permit the building supply to be shut off at the main without the necessity of excavating in the street. Another object of my invention is to provide a device of this character which will be extremely simple in its operation, which can be cheaply made and installed; and is so designed that the person operating the shut-off can positively determine whether the cock at the main is shut or open. With these objects in view, my invention includes the novel elements and the combinations and arrangements thereof described below and illustrated in the accompanying drawing in which—

Fig. 1 is a fragmentary, transverse section of a street showing a water main and my shut-off applied thereto;

Fig. 2 is a fragmentary perspective view showing the application of my device to a water main located inside the curb line;

Fig. 3 is a plan view of an element of my device;

Fig. 4 is a vertical section of Fig. 3 in the plane 4—4; and

Fig. 5 is an enlarged section view of Fig. 1 in the plane 5—5.

Referring to the drawing, 1 represents a street pavement, 2 a curbing, and 3 is a sidewalk.

In Fig. 1, I have shown a water main 4 running parallel to the curbing 2 but at some distance therefrom and under the street pavement proper. 5 is the usual service tap made in the top of the main and provided with the usual shut-off 6. The service shut-off is preferably of the type which is fully closed or opened by a 90° rotary movement of the cock.

Referring to Fig. 1, a shaft 7 having a recess 8 at one end thereof and fitting over a complementary projection on the service shut-off cock extends at right angles from the main to a point somewhere below the sidewalk 3 and on the sidewalk side of a vertical plane extending downwardly through the inside of the curbing. The inner end of the shaft 7 is provided with a projection 9 extending into and coaxing with a complementary recess 10 (see Figs. 3 and 4) in the short shaft 11, which is preferably made an integral part of bevel gear 12. A second bevel gear 13, having a short, vertically-extending shaft 14, meshes with the bevel gear 12. Both of these gears preferably have the same number of teeth so that when gear 13 is rotated $\frac{1}{4}$ of a revolution, gear 12 will also rotate $\frac{1}{4}$ of a revolution and thereby either completely open or shut off the service cock 5 through the shaft 7 connected thereto.

The bevel gear assembly is represented generally by the numeral 15 and is shown in detail in Figs. 3 and 4. This unit comprises a cast iron housing 16, the exterior of which is preferably cylindrical, as shown at 17 in Fig. 3, and the interior, transverse, cross-section of which is as shown by the dotted lines 18 in the same figure. In other words, the interior is not entirely cylindrical in cross-section but is provided with a flat vertical surface 19 against which a shoulder 20 on bevel gear 12 rests. The bearing for the shaft on bevel gear 12 is provided in the side of the housing 16 and the top of the housing is provided with a cylindrical opening 21, forming a bearing for the short shaft 14 which is preferably made integral with gear 13. The top of shaft 14 is provided with a projection 28 designed to interfit with a complementary recess in a vertical shaft so that the gear 13 can be turned from above. Extending through the top of the cast iron housing at the side of the opening 21 is a set screw 22 provided with a lock nut 23. 55

The lower end of this set screw rests upon the upper flat side of gear 13, as shown at 24, and serves to keep gear 13 in mesh with gear 12. It will be noted that there is considerable clearance provided between the inside top of the housing 16 and the top or back of gear 13 so that by loosening and raising the set screw 22 the gear 13 may be raised entirely out of mesh with and above gear 12 and gear 12 may then be pushed into the housing and taken out, whereupon gear 13 may be dropped out of the bottom of the housing. To prevent the entrance of dirt to the housing and also to provide a suitable foundation therefor the opening 25 in the bottom is closed by means of a plate 26 secured to the housing by means of screws 27.

The bevel gear assembly is covered and protected by a vertically extending pipe 29, the bottom of which rests upon the plate 26. Inasmuch as mains are laid at different elevations below the surface of the roadway or the surface of the sidewalk, a second protecting pipe 30 is telescopically fitted within the pipe 29 to provide vertical adjustment, and inside of this last mentioned pipe and extending vertically is a shaft 31 having a slot 32 at the bottom which is complementary to and fits over the projection 28 on the extremity of the shaft 14. In order to hold the vertical shaft 31 approximately in the center of the pipe 30, it is bent, as shown at 33 and 34 in Fig. 2 and its upper end 35 terminates some distance below the sidewalk level 3. The pipe 30 is closed with the usual cap 36 which is at or about the sidewalk level and is readily removable to shut off or turn on the water.

In order to close or open the service cock on the main, a suitable key is provided which is dropped down through pipe 30 and over the end 35 of the vertical shaft 31. If the service cock is open, by turning this key 90° in either direction the service cock may be closed.

Where the main is under the sidewalk, the shaft 7 is, of course, unnecessary, and the bevel gear assembly may be placed directly upon top of the main; the slot 10 in the shaft of bevel gear 12 in such case being fitted over the projection 6 on the service cock. The projection at the end of shaft 14 is provided with an opening 37 through which a pin may be inserted to secure the vertical shaft 31 thereto. Likewise, the shaft 11 on bevel gear 12 is provided with an opening 38 for the insertion of a pin extending through the projection 9 on shaft 7 or, when the device is applied as shown in Fig. 2 through an opening in the shut-off lug on the service cock. It is also to be understood that where the device is applied as shown in Fig. 1 the shaft 7 is secured to the shut off lug on the service cock by means of a similar pin.

Referring to Fig. 5, which is an enlarged section in the plane 5-5 of Fig. 1, it is to be noted that the shaft 7 is enclosed within a pipe or housing 39. Inasmuch as the entire device is buried in the dirt, this housing 39 serves to protect the

shaft 7 and to make it more easily turnable than would otherwise be the case if exposed.

I prefer to make the gears 12 and 13 with their shafts, and the shaft 7, of brass, bronze or other material which will not rust or corrode when exposed to moisture. 5

From the foregoing, it will be apparent that I have provided a very simple and cheap means whereby a service line may be shut off at the main without the necessity of excavating the 10 roadway. Where a street is paved and such an excavation is necessary, it practically ruins the pavement because of settlement due to the compressibility of the soil underneath.

What I claim is:

1. In a device of the character described, an inverted cup-like housing, a first bevel gear located within said housing having a short shaft integral therewith and rotatively mounted in the side thereof, a second bevel gear normally in 20 mesh with said first gear and having a short shaft integral therewith and rotatively mounted in the top of said housing; said second gear and shaft being axially slidable in said housing to a position out of mesh with said first gear whereby said 25 first gear may be removed, and means supported by said housing and in engagement with said second gear for normally maintaining the same in mesh with the first said gear.

2. In a device of the character described, an 30 integral enclosing housing open at the bottom, the top wall and a side wall of which are provided with respective openings, first and second gear members each comprising a gear and a short integral shaft extending into the respective 35 openings and having their bearings in the walls of said housing surrounding the same, the first gear being spaced from the adjacent wall a distance sufficient to permit inward axial movement of the second gear, and a screw mounted in 40 the top wall of said housing and normally engaging the rear side of said second gear for normally retaining said gears in mesh and permitting removal thereof through the interior and bottom of said housing.

3. In a device of the character described, an integral enclosing housing provided with an open bottom normally closed by a detachable plate forming a support therefor, the top wall and a side wall of which housing are provided with respective 45 openings, first and second gear members each comprising a gear and a short integral shaft extending into the respective openings and having their bearings in the walls of the housing surrounding the same, the first of said gears being spaced from the adjacent wall a distance 50 sufficient to permit inward axial movement of the second gear, and means mounted in said housing and engageable with said first gear for normally retaining said gears in mesh whereby 55 said gears may be removed from the interior and bottom of said housing.

EUGENE MILLER.
